DISTILLATION OF HYDROCARBON OIL

Max G. Paulus, Casper, Wyo., assignor to Standard Oil Company, Whiting, Ind., a corporation of Indiana

Application October 11, 1930, Serial No. 488,120

5 Claims. (Cl. 196—49)

The present invention relates to the distillation of hydrocarbon oils and refers more particularly to the distillation of such oils under superatmospheric pressure for the production of lower boiling hydrocarbon oils from relatively higher boiling hydrocarbon oils. The invention is particularly concerned with an improved method and apparatus for separating from heavy residual products produced in such a distillation process, certain lower boiling products which are of the type desired as the final low boiling product and/or of the type which may be subjected to further pressure distillation and thereby converted into the desired low boiling oils.

15 The invention will be fully understood from the following detailed description in conjunction with the accompanying drawings, in which:

Figure 1 illustrates, partly in section and in part diagrammatically, apparatus suitable for carrying out the invention; and

Fig. 2 is an enlarged vertical sectional view of the apparatus employed for separating lighter vaporous products from the residual products of the distillation operation.

25 The apparatus shown in Fig. 1 of the drawings is of the type described in a co-pending application of myself and others, Serial No. 253,976, filed February 13, 1928. In the operation described in this application, the tar or unvaporized hot oil is withdrawn from the bottom of the shell-still and passed to a low pressure chamber wherein certain of the lighter constituents thereof separate as vapors, the remaining unvaporized portions being returned to the still for further treatment, or removed from the system, or both. Considerable difficulty due to coke formation has been experienced within the low pressure separating chamber, causing the lower end of the same to become plugged and necessitating frequent shutdowns for removal of the coke. I have discovered that this tendency of coke to plug up the lower end of this chamber can be entirely prevented by subjecting the heavy unvaporized oil or tar therein to substantial agitation.

40 It is to be understood, however, that the solution of the problem of preventing the accumulation of coke is not limited to a separating step in conjunction with this particular form of distillation operation, but may be employed with a similar separating operation in connection with any other pressure distillation operation wherein heavier oils are converted into lighter or lower boiling oils.

45 Referring more in detail to the drawings, and particularly to Fig. 1, the numeral 5 indicates a

suitable oil container, preferably a horizontal, cylindrical shell or still adapted to withstand high internal pressure and to contain a substantial body of oil undergoing treatment. The shell or still 5 is mounted upon a suitable furnace setting 6, and is protected from the direct heat therefrom. Within the furnace setting there are provided a large number or bank of inclined tubes 7, the lower ends of which communicate with a lower header 8 and the upper ends of 5 which communicate with an upper header 9. The lower header 8 communicates with a vertical pipe 10 which extends upwardly out of the furnace setting through the wall of the shell 5 and for a short distance therewith. The upper end 10 of this tube or pipe 10 forms a seat for a closure member 11 mounted on the stem of a rod 12 threaded through a boss 13 on the upper part of the shell 5, the rod being operated by a hand wheel 14. It is readily apparent that, by operation of the rod 12, the upper end of the tube or pipe 10 may be closed to prevent communication with the contents of the shell 5 or may be opened to permit free communication therewith.

15 The upper header 9 likewise communicates with an upright pipe or tube 15 which enters the shell 5. The pipe 15 is surmounted by a hood or bell 16, the bottom of which is below the outlet of pipe 15.

20 From the upper part of the shell 5 the vapor outlet 17 communicates with a suitable reflux condenser or dephlegmator 18, illustrated diagrammatically. Reflux condensate formed therein is returned by the pipe 19 to the interior of the pipe 10 in the upper portion thereof. Vapors uncondensed in the reflux condenser 18 are discharged to a suitable final condenser and pressure controlling means, such as are commonly employed in the art and are not shown herein.

25 From a point above the bottom of the shell 5, a conduit 20 provided with a pressure release valve 21 and control valve 22, leads to a conduit 23, preferably formed with gradually expanding portions and opening into a reduced pressure drum or chamber 24. Within the drum 24, the conduit 23 opens downwardly above a deflector 25 some distance above the bottom of the drum. In the upper portion of the drum there are provided a plurality of baffle plates 26 of any suitable form, or other suitable means for preventing entrainment of unvaporized liquids by the vapors leaving the drum.

30 The lower portion of the drum contains suitable oil agitating means which may comprise a bladed propeller 24' carried by a horizontal shaft 55

25'. The agitator 24' is substantially spaced from the sides and bottom of the drum 24 and is revolved at such a speed that the oil in the bottom of the drum will be thoroughly agitated. 5
5 The shaft 25' is preferably journaled in a suitable stuffing box 26' secured to a wall of the drum 24 in a leak-proof manner. From the upper portion of the drum, the vapor conduit 27 leads vapors to the lower portion of a column 10 or tower 28, illustrated diagrammatically as a bubble tower. The plates in the tower 28 may be of any desired form.

At a suitable intermediate point in the tower 28, the feed pipe 29 enters and may be employed 15 for the supply of a hydrocarbon oil cooling medium or for the supply of fresh oil fed to the unit. A second supply pipe 30 enters the upper portion of the tower and may be employed for supplying thereto a cooling medium of a lower range of boiling points, such as, for example, a condensate from the vapors evolved from the tower 28. From the upper portion of the tower, a vapor conduit 31 leads to any suitable condensing means (not shown).

25 Condensate formed in the fractionating column or tower 28 and collected in the base thereof is withdrawn through valved pipe 32 and forced by pump 33 through the valved pipe 34 to an intermediate point in the fractionating column 18, from which it passes, together with reflux condensate, through pipe 19 into the still 5.

From the base of the drum 24, unvaporized oil is discharged through the valved pipe 36 leading to a tar cooler or heat exchanger 41, from which the cooled unvaporized oil or tar is discharged 35 through the line 42.

A valved line 37 leads from the bottom of the still chamber 5 whereby the still may be drained. A line 38, provided with a pressure reducing 40 valve 39, leads from the top of the still chamber 5 and is connected to line 20 at a point beyond the pressure reducing valve 21, whereby vapors may be withdrawn from the still 5 and admixed with the heavy oil or tar withdrawn from the still through line 20.

45 The operation of the heretofore described apparatus is described in detail in the aforementioned application of myself and others Serial No. 253,976, with the exception of course of my novel separating drum 24 equipped with means for agitating the unvaporized heavy oils or tars therein. For the present purposes it will suffice to say that during operation of the apparatus, portions of the heavy unvaporized oil or tar formed in the large shell 5, during the distillation operation carried out under suitable superatmospheric pressure, are withdrawn from the lower portion of the shell 5 through line 20 and passed to the drum 24 which is maintained under substantially lower pressure, for example, approximately atmospheric pressure. In the drum 24 a separation of vapors from unvaporized oil takes place, the vapors passing through conduit 27 into the column 28 wherein they are subjected to suitable fractionation, the heavier fractions being condensed and passed back into the system through the line 34. The heavy unvaporized oils or tars accumulate in the bottom of drum 24 and are withdrawn therefrom through line 36 from which they are discharged 60 into cooler 41 and from there out of the system.

70 During the operation the propeller blade 24' is rotated to cause the heavy unvaporized products in the bottom of drum 24 to be subjected to substantial agitation. I have found that this agitation of these heavy products prevents substan-

tial deposition of coke within the drum 24 and makes it possible to operate the drum continuously for periods as long as six months. Without such agitation the lower end of the drum often becomes plugged up with coke within a few days 5 and it was not possible to operate the drum for more than two or three weeks without it becoming plugged up with coke.

It will be understood that the present invention is applicable to flash type separation chambers 10 for separating the more volatile fractions from the heavy residual or tarry products produced in any pressure distillation or cracking operation.

I claim:

1. Apparatus for the conversion of higher boiling hydrocarbon oils into lower boiling ones that comprises a chamber in which the oil is adapted to be maintained at cracking temperature under superatmospheric pressure, means for withdrawing vapors from said chamber, a flash chamber 20 formed with a conical bottom and adapted to be maintained under pressure materially lower than that in said first named chamber, means for withdrawing residue from said first named chamber and passing it directly to said flash chamber, 25 means for withdrawing vapors from an upper part of the flash chamber, an outlet line extending from the conical section of the flash chamber and adapted for the withdrawal of residue therefrom, a propeller element mounted within said conical section and adapted to produce movement in the residue substantially transverse to the path of the residue flowing to said outlet line to thereby prevent substantial deposition and accumulation of coke in the conical section in the path of the outflowing residue.

2. Apparatus for the conversion of higher boiling hydrocarbon oils into lower boiling ones that comprises a chamber in which the oil is adapted to be maintained at cracking temperature under 40 superatmospheric pressure, means for withdrawing vapors from said chamber, a flash chamber formed with a conical bottom and adapted to be maintained under pressure materially lower than that in said first named chamber, means for withdrawing residue from said first named chamber and passing it directly to said flash chamber, means for withdrawing vapors from an upper part of the flash chamber, an outlet line extending from the bottom of the conical section, a propeller element mounted in said conical section on an axis substantially transverse to that of the path of the outflowing residue and adapted to effect agitation therein to prevent substantial deposition and accumulation of coke in the path of 55 the outflowing residue.

3. Apparatus for the conversion of higher boiling hydrocarbon oils into lower boiling ones that comprises a chamber in which the oil is adapted to be maintained at cracking temperature under 60 superatmospheric pressure, means for withdrawing vapors from said chamber, a flash chamber adapted to be maintained under pressure materially lower than that in said first named chamber, means for withdrawing residue from said first named chamber and passing it directly to said flash chamber, outlet means disposed in the bottom portion of said flash chamber for withdrawing unvaporized tar-like residual products from 70 said second chamber, a restricted section in said flash chamber leading to said outlet and agitating means in said restricted section immediately adjacent said outlet and disposed to impart movement to outgoing residual products substantially 75

transverse to the movement of said products being withdrawn from said chamber.

4. In an apparatus for treating hydrocarbon oils, a chamber adapted to contain tar-like residual products, said chamber comprising an outer shell, a section of reduced dimensions in the bottom portion of said shell, outlet means leading from said section of reduced dimensions, a shaft bearing secured to said shell, a shaft rotatably mounted in said bearing and extending into said section of reduced dimensions, agitating means secured to said shaft adjacent said outlet means and disposed to agitate the material in said section of reduced dimensions passing to said outlet, thereby preventing substantial deposition and accumulation of coke in the path of the outgoing residue.

5. In an apparatus for treating hydrocarbon oils, a chamber adapted to contain viscous tar-like residual products, said chamber comprising an outer shell, a section of reduced dimensions in the bottom portion of said shell, outlet means leading from said section of reduced dimensions for withdrawing tar-like residual products, a shaft bearing extending through said shell in an angular relation to said outlet means, a shaft rotatably mounted in said bearing, agitating means secured to said shaft adjacent said outlet and disposed to locally agitate material passing to said outlet to thereby prevent substantial deposition and accumulation of coke in the path of the outgoing residue.
